UNITED STATES PATENT OFFICE.

FREDERICK S. GALLAGHER, OF YONKERS, NEW YORK.

HOPPER-DOOR-OPERATING MECHANISM.

Application filed November 6, 1922. Serial No. 599,365.

To all whom it may concern:

Be it known that I, FREDERICK S. GALLAGHER, residing at Yonkers, county of Westchester, State of New York, and being a citizen of the United States, have invented certain new and useful Improvements in Hopper-Door-Operating Mechanism, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

This invention relates to railway freight cars of the hopper type used for hauling coal, ore and the like which have doors so constructed that the entire load or the major portion thereof is discharged from the car when the doors are open, which doors must be moved to closed position before the car is moved to prevent the door from being damaged.

The doors usually form a part of the wall or floor or other containing part of the car and as such cars are frequently loaded from tipplers to the height of the door its supporting mechanism must be very strong to withstand not only the impact but the load falling from the tippler and also the impact due to the movement of the car in transit.

Furthermore, the door supporting or locking mechanism must be absolutely positive because the failure of these parts would result in the load being discharged on the rail thereby derailing and wrecking the train as well as causing the loss of the lading.

One of the objects of this invention is to obtain a door mechanism which is positive on account of its lock to the locked feature.

Door locking mechanisms generally in use are so arranged that just as the door reaches its closed position the three pivot points of the mechanism are just a little beyond the center so that the tension on the mechanism due to the load tends to lock the door instead of unlocking it. This is known as the eccentric lock and will be hereinafter described.

When the door is open the first fraction of a revolution of the operating shaft throws the fulcrum point beyond the center which results in the door being rapidly forced open with a sudden revolutionary movement of the shaft and its operating wheel or wrench which, in numerous cases, has resulted in knocking the operator down or otherwise injuring him. This is particularly dangerous when the car is being unloaded on a trestle in construction work or on an unloading dock at the seaboard.

Another object of the invention is to obtain a safe means of unlocking the door mechanism to prevent the injury to the operator described above.

As the operating shaft on such cars is usually as long as the width of the car or about five feet it is necessary to support it on at least three points which frequently results in the shaft binding owing to the bearings getting out of alignment due to the sagging or distortion of the car body.

Another object of this invention is to divide the operating shaft into two parts and connecting the two by a flexible joint to obviate this troublesome feature.

In the drawings:

Fig. 1 shows a fragmentary plan view of a hopper car with the invention applied thereon.

Fig. 2 shows a fragmentary side elevation of a hopper car with the invention applied thereon, having the door closed.

Fig. 3 shows a fragmentary side elevation of a hopper car with the invention applied thereon, having the door open.

Fig. 4 is a fragmentary section of a hopper car.

Fig. 5 is a perspective view of the operating unlocking mechanism.

Figs. 6, 7, 8, 9 and 10 show the various positions assumed by the operating and winding shaft in closing and opening the door.

Numeral 1 is the side wall of a hopper car, 2 the floor sheet, 3 the center hopper sheet and 4 the side hopper sheet respectively of the car. Numeral 5 is the door hinged to the floor sheet 2 by hinge 6. The lower part of the door 5 is provided with eye bolt 7 connected to arm 8 at point 12 which in turn is pivoted to eccentric arm 9 at point 13 which is rigidly secured to operating shaft 10 by set screw 11, which shaft 10 is supported by journals 21 and 22.

at any convenient place on the car. Eye bolt 7 is threaded at one end and provided with nuts 14 for adjustment. Operating shaft 10 is operatively flexibly connected to winding shaft 15 which is journaled to any convenient part of the car, as shown at 16. This operating shaft is provided with ratchet 17 and pawl 18 and manual winding wheel indicated in dot and dash lines as 19 or may be provided with a square portion 20 for engagement with the operating wrench.

Generally operating shaft 10 and winding shaft 15 are made in one piece so that 15 a rotation of this shaft through eccentric arms 9 and arms 8 and eyebolt 7 actuate to close the door and at the end of such movement a straight line drawn from connection 12 to connection 13 falls below the 20 center of the winding shaft, as shown in dot and dash lines on Fig. 2. Thus the thrust due to the door and the load thereon has a tendency to hold the door closed instead of opening it. This feature I do 25 not claim as new with me. To open the door operating shaft 10—15 is rotated in the opposite direction until the line drawn between connections 12 and 13 rises above the operating shaft at 23 at which time 30 the door flies open due to its own weight and the weight of the load thereon. This constant acceleration of the rotary motion of the shaft which is transmitted to the winding wheel 19 causes a sudden and rapid 35 movement of this wheel 19 or the operating wrench causing the operator to lose his grip or be knocked to the ground or be injured by the operating wrench flying around and striking him and if he happens to be operating the car on a trestle or dock he is 40 in a precarious position.

It will readily be seen that if the two shafts 10 and 15 are in one piece and journals 21, 22 and 16 should become out of 45 alignment owing to the distortion of the car that this one shaft would bind which would result in the mechanism becoming inoperative.

My improvement relates to having the 50 operating shaft made independent of the winding shaft and mounted on the car independent thereof. The winding shaft 15 is supported on the car body at its outer end and flexibly connected to the operating shaft at its inner end so that the probabilities of these shafts binding due to the distortion of the car are practically eliminated.

The end of the winding shaft 10 is provided with a lateral extending portion 24

and the inside end of winding shaft 15 is 60 provided with a lateral extending portion 25 which is provided with an eye 26 which is journaled on the winding shaft 10 adjacent the lateral portion 24 so that the main part of the winding shaft 15 is in contact with the lateral extending portion 24 65 of the operating shaft at point 27.

This operative flexible joint between the operating and winding shafts operates as 70 follows: Fig. 6 shows part of the operating shaft 15 in section and the lateral extending portion of the winding shaft when the door is in closed and locked position. In this position a line drawn from points 12 to 13 in Fig. 2 fall below point 23 which 75 is the center of the operating shaft. To open the door the operating shaft is rotated, as shown by the arrow in Fig. 7, until it comes in contact with the lower part of the lateral extension, as shown in Fig. 7. 80 A continuation of this rotative movement moves the lateral extension until it assumes position shown in Fig. 8, whereupon the line drawn between points 12 and 13 in Fig. 2 rises above point 23 in Fig. 2 so that 85 the door swings open by gravity until the lateral extension of the winding shaft and the operating shaft assume position shown in Fig. 9. When it is desired to close the 90 door the operating shaft is rotated, as indicated by the arrow in Fig. 10, until it comes in contact with the lower portion of the lateral extension and this rotative movement is continued until the door is closed and locked and the operating shaft and the 95 lateral extension of the winding shaft assume position shown in Fig. 6.

While the drawings show the winding shaft mounted on the operating shaft at 100 its inner end it is understood that it is still within the scope of this invention to mount the outer end of the operating shaft on the inner end of the winding shaft.

What I claim is:

1. In an operating means for hopper car 105 doors comprising a winding shaft having a lateral extension at one end, and an operating shaft having a lateral extension at one end, provided with an aperture for journaling it upon said winding shaft.

2. In an operating means for hopper car 110 doors comprising a winding shaft having a lateral extension at one end, and an operating shaft having a lateral extension at one end, said winding shaft provided with 115 an aperture for journaling it upon said operating shaft.

FREDERICK S. GALLAGHER.
